UNITED STATES PATENT OFFICE.

ALFRED L. HUGHES, OF COLORADO SPRINGS, COLORADO.

AUTOMATIC VEHICLE GATE.

Application filed August 29, 1927. Serial No. 216,039.

This invention relates to automatic vehicle gates, designed to be opened and closed through the weight of the vehicle as the same passes upon or leaves the specially 5 provided tread boards of the apparatus.

The prime object of the invention is to provide a relatively simple, practical and efficient self-operating gate for use upon roads, drive-ways or garage doors.

10 In the drawing

Figure 1 is a perspective view showing a gate as mounted upon a drive-way and partly open, a section of the drive-way being excavated from around the working elements, 15 and sections of the protective housings of the working elements being broken out, for the purpose of clearly illustrating those parts;

Figure 2 is a vertical transverse section through the two gate posts, runway and the 20 operating mechanism below the runway.

The invention includes a vehicle run-way 1 positioned in the drive-way 2 immediately under the gate 3. Tread boards 4 are oppositely hinged at the points 5 in one of the 25 wheel-ways 6 at one side of the gate 3, the free ends 7 of these tread boards being spaced apart longitudinally just enough to permit the gate 3 to be positioned between them transversely upon the drive-way 2. The gate 30 is slidably suspended from the trolley rail 8 which runs over rollers 9 depending from the cross bar 11 supported between the hollow gate posts 10 which are anchored in the run-way 1. The hollow posts 10 are also 35 provided with lateral, inwardly turned cable apertures 12 at their upper ends and their hollow interiors are connected with the under side of the run-way 1 through the lower cable apertures 13 formed through the said 40 run-way in axial alignment with the said posts. Within a cavity 14 formed below the run-way 1 and tread boards 4 a housing 15 is positioned and preferably secured to the under side of the said run-way. A rectangular frame 16 is anchored within the housing 15, the same being disposed vertically below and in longitudinal alignment with the tread boards 4. The frame 16 includes a 45 plate 17 which is fastened to the under face of the run-way 1, vertical side bars 18 depending from the plate 17 at either side of the post 10 at that side of the run-way, and a lower cross bar 19 which rigidly connects the lower ends of the two side bars 18.

50 The frame 16 is further supported by means of a brace 20 extended angularly from

the cross bar 19 to the under face of the run-way 1. Upon the two vertical side bars 18 are mounted rack guide rails 21 and racks 22 are slidably mounted therein, the same 60 fastening outwardly. Rack bars 23 are passed through apertures 24 formed through the run-way 1 and have their upper ends hingedly connected at 25 with the free ends of the tread boards 4 and their lower ends 65 hingedly connected at 26 with the upper ends of the said rack bars 23.

The lower ends of the rack bars 23 are rigidly connected by means of a cross bar 27. Retractable springs 28 having their ends 70 attached at 29 to the cross bar 27 and at 30 to the under face of the run-way 1, serve to normally throw the rack bars 23 and the free ends 7 of the tread boards 4, upwardly. A pulley shaft 31 is journaled in bearings 32 horizontally across the faces of the rack bars 23. Pinions 33 are rigidly mounted upon the ends of the shaft 31, in mesh with the teeth 34 of the rack bars 23, and gate opening and closing pulleys 35 80 and 36 respectively are rigidly mounted upon the medial part of the shaft 31 immediately below the post 10 at that side of the runway. Another pulley wheel 37 is mounted upon a shaft 38, the latter shaft being journaled in bearings 39 depending from the under face of the run-way 1 immediately below the opposite gate post 10. Small pulleys 40 are also journaled within the upper ends of the posts 10 at the cable apertures 12. The 90 gate 3 being closed, a gate opening cable 41 is fastened by one end at the point 42 upwardly upon the gate opening pulley 35, and is then brought down under that pulley with a left hand turn as indicated by the 95 arrows shown on the pulley 35, and is extended under the lower pulley 37, up through the post 10 at that side of the runway, over its upper cooperating pulley 40, and has its free end then led out through the adjacent aperture 12 and brought back to the opposite or starting end of the gate 3 immediately over the tread boards 4, and is fastened to a pin 43 extended from the upper bar of the gate 3. With this cable 41 drawn properly taut, downward pressure 100 upon either of the linked tread boards 4, will operate to open the gate 3, the same sliding laterally upon the rail 9. A similar gate closing cable 44 has one end fastened at 45 105 upwardly upon the gate closing pulley 36, is then led with a right hand turn around the 110

5 pulley as indicated by the arrow shown on the pulley 36, and extended up through the adjacent post 10, over the upper pulley 40 of that post, out through the adjacent aperture 12 and has its free end likewise secured to the pin 43, this cable of course being also drawn properly taut. Downward pressure upon either of the tread boards 4 will operate to close the gate 3 when it is open. It 10 will be noted that the cables 41 and 44 are passed over their respective pulleys in opposite directions.

15 A slotted housing 46 may be provided for enclosing the exposed portions of the cables 41 and 44, where they connect with the pin 43 and travel along the upper part of the gate in the opening and closing operations, the ends of this housing being supported between the posts 10.

20 In use the wheels of a vehicle running upon the tread boards 4 will open the gate 3 in the manner described; and as the vehicle passes through and the wheels quit the boards 4, the springs 28 operate to close the 25 gate.

30 While I have herein described a certain specific manner and method of constructing and assembling the elements of my invention, it is understood that I may vary from the same in minor details, not departing from the spirit of my invention, so as best to construct a practical device for the purpose intended, as defined in the appended 35 claims.

40 35 I claim:

45 1. An automatic vehicle gate for a driveway, comprising a runway positioned across the drive, the runway having two cable apertures through its opposite margins at the sides of the drive; two hollow posts anchored upon the runway immediately over the said cable apertures, the said posts having upper lateral cable apertures turned inwardly; cable pulleys journaled at the upper cable apertures; a lower cable pulley jour-

naled below the runway at one of the cable apertures thereof; a horizontal cross-bar connecting the upper ends of the gate posts; a gate slidably suspended from the said crossbar; two tread boards reversely hinged 50 within one of the wheelways of the runway at the opposite side of the runway from the said lower cable pulley, and having their free ends disposed adjacent opposite sides of the gate; a rectangular frame secured 55 to the under side of the runway below the tread boards, the frame being located vertically and in longitudinal alignment with the tread boards; connected rack bars slidably and vertically mounted upon said frame 60 immediately below the free ends of the tread boards and operatively connected thereto; a shaft disposed across the frame and the said rack bars, the ends thereof being journaled in the frame; pinions on the ends of 65 the shaft in mesh with the racks of the rack bars; gate opening and closing pulleys medially mounted upon the shaft; gate opening and closing cables attached to their respective pulleys and extended up through 70 the hollow posts over the cable pulleys and operatively attached to the said gate; and means for resiliently holding the tread boards in their elevated position.

75 2. In combination with a vehicle gate slidably mounted across a drive, tread boards at opposite sides of the gate at one end thereof and adapted for vertical movement; means for normally maintaining the tread boards in their uppermost position; rack 80 bars connected with the said tread boards; a shaft journaled across the rack bars; pinions on said shaft in mesh with the rack bars; gate opening and closing pulleys on said shaft; and gate opening and closing 85 cables mounted over said pulleys and operatively connected with said gate.

In testimony whereof I affix my signature.

ALFRED L. HUGHES.
